BARREL LOCKING MECHANISM FOR BREAKDOWN GUNS

Filed Aug. 27, 1925

FIG. 1.

FIG. 2.

FIG. 3.

By

Louis P. Smith Inventor

J. H. Bryant Attorney

UNITED STATES PATENT OFFICE.

LOUIS P. SMITH, OF ITHACA, NEW YORK, ASSIGNOR TO ITHACA GUN COMPANY, OF ITHACA, NEW YORK, A CORPORATION OF NEW YORK.

BARREL-LOCKING MECHANISM FOR BREAKDOWN GUNS.

Application filed August 27, 1925. Serial No. 52,893.

This invention relates to new improvements in barrel locking mechanism for breakdown guns.

The primary object of the invention is 5 the provision of a barrel locking mechanism which may be manually thrown into an unlocked position and will be held in such position by an automatic trip member.

A further object of the invention is the 10 provision of a trip which will automatically move into a position for holding a barrel locking mechanism in its unlocked position while the barrel breech is open and will automatically move into a barrel lock releasing 15 position when the barrel breech is closed.

Other objects and advantages of the invention will be apparent during the course of the following description.

In the accompanying drawing forming a 20 part of this specification and in which like numerals are employed to designate like parts throughout the same,

Figure 1 is a fragmentary side elevational view of a portion of a gun frame having 25 mounted therein a barrel locking mechanism and an automatic trip for holding the said mechanism in its unlocked position while the barrel breech is open,

Figure 2 is a similar view to Fig. 1 but 30 shows the barrel locking member in its unlocked position and held in such position by a trip member, and

Figure 3 is a top plan view of the trip member shown in Figs. 1 and 2.

In the drawing, wherein for the purpose 35 of illustration is shown a preferred embodiment of this invention, the numeral 5 designates a gun frame having the bottom wall 6 and end wall 7 forming a barrel breech receiving portion.

Rotatably mounted within the frame 5 is a barrel locking bolt 8 which is of the rotatable type and is rotated by means of the yoke 9 which is carried by the pivotally mounted 40 post 10, the said yoke 9 having an arm 11 which projects into a socket 12 formed in the inner end of the bolt 8. This bolt 8 is formed with a slot 13 which communicates with a second slot 14 forming a barrel locking portion 15, in the said bolt.

The bolt 8 is provided with a longitudinally extending groove 16 which is formed in the periphery of the bolt and at the diametrically opposite point to the slot 13. It 55 is to be understood that this groove 16 will

be positioned at the lower side of the bolt 8 when the latter is in its barrel unlocking position, as illustrated in Fig. 2.

Slidably mounted in the frame 5 is a substantially U-shaped trip 17 which has its longer side formed with a reduced end 18 normally held in engagement with the periphery of the rotatable bolt 8 by the spring 19. The shorter side 20 of the trip 17 is arranged in alinement with a hole 21 formed in the bottom wall 6 of the barrel breech receiving portion of the frame 5.

It will now be seen that when the post 10 is rotated for causing the barrel locking bolt 8 to be rotated to arrange its slot 13 on the upper side of the bolt, as illustrated in Fig. 2, the groove 16 in the periphery of the bolt 8 will have been moved into register with the reduced end 18 of the U-shaped trip 17. This upward movement of the trip 17 will groove 16 will permit the spring 19 to function to shift the trip bodily upwardly for moving the reduced end 18 into said groove. This upward movement of the trip 17 will cause the shorter side 20 of the trip to project through the opening 21 in the frame wall 6 so that the end of the side 20 will be arranged in the barrel breech receiving portion of the frame. It will be understood that after the bolt 8 has been rotated into its unlocked position, the trip 17 will not move into its bolt holding position until the barrel breech has been opened or moved out of the portion of the frame formed by the walls 6 and 7. When the barrel breech is returned into the portion of the frame 5 formed to receive it, the barrel breech will engage the shorter side of the trip 17 and will force the entire trip downwardly for releasing the bolt 8.

It is desirable to have the bolt 8 automatically move into its barrel locking position when the barrel breech has engaged and shifted the trip 17. To bring about this movement of the bolt 8, a spring pressed cap 22 is provided and bears against a ball 23 formed on the screw 24 and projecting from the side of the bolt 10. This spring pressed cap 22 will provide the desired power or force for returning the post 10, the yoke 9, and the bolt 8 into their barrel locking positions.

It is to be understood that the form of this invention herewith shown and described is to be taken as a preferred example of the

same, and that various changes in the shape, size, and arrangement of parts may be resorted to without departing from the spirit of the invention or the scope of the subjoined claim.

Having thus described the invention, I claim:

In a breech loading break-down gun, wherein the breech frame is provided with a rotary locking bolt rotating on an axis substantially parallel to the axis of the barrel, wherein a rocking spindle is journaled in the breech frame to the rear of the locking bolt, and wherein a pendulum-lever is hinged to the rocking spindle and has a ball and socket connection with the rotary lock-

ing bolt, an external recess in said rotary locking bolt, and a vertically slideable substantially U-shaped trip spring-pressed upwardly to normally have the upper end of one leg thereof engaged in said recess of the locking bolt for holding the latter in unlocked position and for simultaneously projecting the other leg of the trip in the path of the barrel whereby the trip will be depressed and released from the locking bolt by engagement of the underside of the barrel with said other leg of the trip when the barrel is moved to operative position.

In testimony whereof I affix my signature.

LOUIS P. SMITH.
